UNITED STATES PATENT OFFICE.

FRANK J. McAVOY, OF CHICAGO, ILLINOIS, ASSIGNOR TO LONDON AUTO SUPPLY CO.,
OF CHICAGO, ILLINOIS, A CORPORATION OF ILLINOIS.

SECTIONAL LIMOUSINE-DOOR.

Specification of Letters Patent. Patented July 20, 1915.

1,146,805.

Application filed June 3, 1912. Serial No. 701,153.

To all whom it may concern:

Be it known that I, FRANK J. McAVOY, a citizen of the United States, and a resident of the city of Chicago, in the county of Cook and State of Illinois, have invented certain new and useful Improvements in Sectional Limousine-Doors; and I do hereby declare that the following is a full, clear, and exact description of the same, reference being had 10 to the accompanying drawings, and to the numbers of reference marked thereon, which form a part of this specification.

In those constructions in which a detachable limousine top is applied to the summer bodies of automobiles, the door construction has occasioned great trouble, inasmuch as the doors in the summer body are narrow and relatively low, and although sufficiently large usually to afford convenient ingress 20 and egress from the body of the car when the limousine top is not in place, prove much too narrow for convenience should the same be continued upwardly of no greater width in the limousine body. This has proven an almost insurmountable objection to the use 25 of removable limousine bodies, inasmuch as in such constructions heretofore it has been usual to remove the doors from the summer body and substitute solid doors to close into the summer body and also the limousine top. The doors when so constructed, are so narrow as to render it difficult for a person 30 of average size to enter the car. This difficulty is increased from the reason that the doors as arranged in the summer body are in such close relation with the seats as to actually reduce the space otherwise available for 35 entry and egress.

The object of this invention is to afford 40 a construction whereby the ordinary and usual doors in the summer body are utilized as a lower section when the limousine body is in place thereon, and a wider door affording an upper section is secured thereto to 45 open and close therewith to afford a large and conveniently spaced opening into the car.

It is an object of the invention also to 50 utilize all parts of the summer body, including the doors, without any change whatever, and to mount and secure the limousine body thereon, including the wider door sections, to afford a wind and water-proof construction, in which the operation of the relatively 55 small lower door section serves to simul-

taneously operate the larger upper door section.

The invention (in its preferred form) is illustrated in the drawings and hereinafter more fully described.

In the drawings: Figure 1 is a side elevation of an automobile equipped with a summer body and having mounted thereon a detachable limousine body provided with doors embodying my invention. Fig. 2 is an 60 enlarged, fragmentary side elevation, partly broken away, to illustrate the mutual engagement of the doors. Fig. 3 is a fragmentary section on line 3—3 of Fig. 2. Fig. 4 is a section on line 4—4 of Fig. 2.

As shown in the drawings: 1, indicates the summer body of the automobile, provided with doors 2, of the usual or any preferred construction. Mounted thereon and detachably secured to the summer body, is a removable limousine top 3, which may be attached in any convenient way to the summer body to afford a secure engagement therewith. Said limousine body is provided with a rear door section 4, and a front door section 5, each arranged above the corresponding door or door section 2, in the summer body, but sufficiently wider than the same to afford convenient ingress and egress from the body of the car for the users thereof. In 75 the construction shown, in which the lower door sections 2, open or swing rearwardly, the upper or limousine door sections 4 and 5, are offset or extend rearwardly beyond the rear edge of the lower door sections, and hingedly connected with any suitable hanging jamb or post by means of suitable hinges 6, and the front edges of said limousine door sections may extend into alinement with the front edges of the lower door sections or forwardly beyond the same, as preferred, although usually the front or swing edges of the door sections are arranged in alinement, as it is thought that a better 80 appearance is afforded thereby.

A downwardly opening groove or slot, indicated by 7, is provided in the bottom rail of the limousine door sections 4 and 5, and engaged therein is a roller 8, secured by means of a suitable cap screw or bolt 9, 105 which extends through said roller and into the top of the lower door section 2, thus positively but movably connecting the respective upper door sections with the corresponding lower door sections. A lock or 110

latch, indicated by 10, is provided in the usual manner on each of the lower door sections 2, or those in the summer body.

The operation is as follows: When it is desired to open the doors, the latch or lock 10, is actuated and the lower door section 2, is swung open, swinging the upper door section simultaneously thereby, as shown in dotted lines in Fig. 3, to open position, owing to the movable connection between the doors afforded by the roller 8, engaging in the groove in the bottom of the upper door section. As the doors swing rearwardly, both door sections are opened to any desired extent, the movement in the lower door section necessitating corresponding movement in the upper door section, thus enabling the passenger to enter or leave the car as conveniently as though the entire door were of the width of the relatively wide upper door section. Of course, the difference in width of said door sections may be as great as desired or necessity may require, for it is obvious that owing to the movable connection between the doors, movement in one must necessitate corresponding movement in the other to the same or a proportional degree. Obviously, in closing the door, when the lower door section is closed and latched, the upper door section also is brought and held in closed position, so that both door sections are operated as desired by actuating the latch for one of the same.

Of course, it is to be understood that details of the construction may be varied. I have shown but one (and that a preferred) embodiment of my invention, and I do not purpose limiting the patent granted on this application otherwise than necessitated by the prior art.

I claim as my invention:

1. In a device of the class described a sectional door embracing a relatively narrow lower door section and a wider upper door section, hinges for each section mounted out of alinement with one another, means physically connecting said door sections necessitating simultaneous and corresponding movement in both, and a latch on one of said sections acting to control both.

2. In a device of the class described a relatively narrow lower door section and a latch

thereon, a wider upper door section, hinges for said respective sections mounted parallel and out of alinement, a longitudinal guide 55 in the rail of one of said door sections, and a roller journaled on the meeting rail of the other, and projecting into engagement with the guide and acting to movably connect the door sections to permit both to be operated 60 and controlled by the latch simultaneously.

3. In a device of the class described a hinged relatively narrow lower door section, a latch thereon, a wider upper section, hinges for each door section disposed out of 65 alinement with one another, said upper door section closing in substantially the same plane with the lower door section, and having a downwardly opening groove extending longitudinally of its bottom rail, and a 70 roller journaled on the top of the lower door section and projecting into said groove, the sides of which afford guides therefor whereby the operation of the lower door section necessitates like simultaneous operation of 75 the upper door section and whereby said latch controls both door sections.

4. In a device of the class described doors of unequal width mounted one above the other and adapted to swing on different axes 80 and means connecting and adapting the same to open and close simultaneously.

5. In a device of the class described, a plurality of offset door sections one disposed above the other and together adapted to 85 close a single opening, said sections hinged to swing on parallel axes, and means connecting said sections adapting the same to open and close simultaneously.

6. A door comprising separately hinged 90 rigid door sections which are arranged one above the other, the hinges of one section being out of alinement with the hinges of the other section, and means connecting said sections for causing them to swing together 95 and permitting a limited movement of one section relatively to the other section.

In testimony whereof I have hereunto subscribed my name in the presence of two subscribing witnesses.

FRANK J. McAVOY.
